Primary Examiner — Eric Goodman

Assistant Examiner — Jennifer L Rempfer

(57) **CLAIM**

I claim the ornamental design for a baby play mat, as shown and described.

DESCRIPTION

FIG. 1 is a folded perspective view thereof;

FIG. 2 is a rear elevation thereof;

FIG. 3 is a front elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines represent stitching and forms a part of the claimed design.
